UNITED STATES PATENT OFFICE.

HENRY TRENCHARD, JR., OF BROOKLYN, NEW YORK, ASSIGNEE TO TENSION ENVELOPE COMPANY, INC., OF BROOKLYN, NEW YORK, A CORPORATION OF NEW YORK.

FASTENER-AFFIXING MACHINE.

Application filed December 31, 1917. Serial No. 209,729.

To all whom it may concern:

Be it known that I, HENRY TRENCHARD, Jr., a citizen of the United States of America, residing in the borough of Brooklyn, in the city of New York and State of New York, have invented an Improvement in Fastener-Affixing Machines, of which the following is a specification.

The present invention relates to paper working machinery and more particularly to a machine for applying fasteners to an envelope or other blank.

It is an object of this invention to provide improved fastener applying mechanism.

The present application is a continuation in part of an earlier application filed by me December 30, 1915, Serial No. 69,392, now Patent No. 1,258,829 dated March 12, 1918.

The invention has been developed and for convenience will be described as embodied in a machine for applying so-called "double button and string" fasteners to envelopes.

For convenience in the description of the particular embodiment of this invention, it may be noted that such envelopes are generally provided with a comparatively stiff fastening washer or button upon the outside of the body of the envelope united thereto preferably by means of an eyelet 25 which is upset to engage the washer and hold it securely in position in relation to the body of the envelope. A similar fastening washer is similarly affixed to the flap of the envelope and preferably a comparatively light reinforcing washer is used upon the inside of the flap; the two being fastened by an eyelet passed through the washers and through the envelope flap. The string, which is used to effect the closure of the envelope, preferably has one end fastened 30 under the eyelet which attaches the cooperating washers to the flap of the envelope.

A preferred embodiment of the invention has been herein selected for purposes of illustration and explanation and is shown in the accompanying drawings, wherein—

Figure 1 is a front elevation of the machine;

Figure 2 is a side elevation viewed from the right of Figure 1;

Figure 3 is a top plan view of the machine with certain parts removed for clearness;

Figure 4 is a vertical section on the line 4—4 of Figure 3;

Figure 5 is a vertical section on the line 5—5 of Figure 3;

Figure 6 is an enlarged view of a portion of Figure 5;

Figures 7, 8 and 9 are detailed views of a preferred eyelet escape mechanism;

Figures 10 and 11 are detail views of a preferred clutch mechanism;

Figure 12 is a view of a preferred eyelet feeding mechanism;

Figure 13 is a detail view of a preferred tape feed actuating mechanism;

Figure 14 is a vertical cross section on the line 14—14 of Figure 1;

Figure 15 is a similar section on the line 15—15 of Figure 1 looking in the opposite direction from the preceding figure;

Figure 16 is an assembly view of a preferred string feeding and cutting mechanism;

Figures 17 and 18 are detail views of the string cutting mechanism;

Figures 19, 20 and 21 are detail views of the string feeding mechanism; and

Figure 22 shows an envelope punched with a fastener such as may be attached by the machine herein shown.

In the following description of the illustrative embodiment of the invention, the general structural features of the machine will first be described and then, in the sequence indicated, the illustrative mechanism for affixing the fastener and washer to the body of the envelope; the illustrative mechanism for forming and affixing the fastener and reinforcing washer to the flap of the envelope; and lastly the illustrative mechanism for feeding, fastening and cutting the string. The washers are shown as annular but they may be of any suitable form as desired.

Referring to the drawings it will be seen that the greater part of the mechanism is mounted upon a bed-plate or table 1 supported upon standards 2. A main shaft 3, 100 journalled in suitable bearings upon the table 1, is provided with a balance wheel 4 and is adapted to be connected with a driving pulley 5 by a suitable clutch mechanism located at the right hand side of the machine. The driving wheel 5 carries a jaw 6 and is, during the operation of the machine, rotated continuously from a suitable source of power. The operation of the machine to affix the "double button and string" 110

fastener" is preferably accomplished in one revolution of the main shaft 3 and the clutch mechanism is therefore designed to rotate the main shaft through one revolution and then automatically disengage. A clutch collar 7 is keyed to the main shaft (see Figures 10 and 11) and is slidable thereon. This collar has jaws 8 to co-operate with jaws 6 on the hub of the driving pulley 10 which rotates freely on the main shaft, and a spring pressed plunger 9 tends normally to force the jaws into engagement. A flange 10 upon the collar 7 has a cam surface 11 and, as shown in Figure 10, this cam surface bears against a stud 12 which holds the collar 7 away from jaws 6. The stud 12 is held normally in the position shown in Figures 2 and 10, by a spring 13 which is attached to the bed of the machine and to a lever 14 passing through the lower end of the stud. A treadle 15 is connected by suitable links 16 and 17 with the lever 14 so that upon depression of the pedal and its immediate release, the collar 7 will be forced to the right in Figure 10 to engage jaws 6 and 8 and rotate the main shaft 3 through one revolution, the stud 12 co-operating with the cam 11 to withdraw the collar 7 toward the end of the single revolution.

As shown in Figure 3 a notched collar 18 is fast to the main shaft 3 and a spring pressed lever 19 engages the notch in the collar 18 to prevent the back lash of the main shaft.

Coming now to the mechanism for affixing the fastening washer to the body of the envelope and referring particularly to Figures 3 and 4, means are provided for feeding through a strip of tape, forming a washer from the tape, feeding an eyelet into the proper position and actuating the washer forming mechanism to affix the washer to the body of the envelope. In Figure 3 it will be seen that a shoe 20 projects from a stationary part of the machine and carries an anvil 21. A light spring guard 22 is fastened to the outer end of the shoe and overlies the anvil 21. This spring serves to press the body of the envelope away from the anvil when the fastening eyelet has been upset and contributes to the speed of operation of the machine by permitting a direct withdrawal of the envelope. The shoe, anvil and releasing spring are shown in section in Figure 4. A light spring 256, see Figure 3, serves to press the envelope flap toward the side of the shoe so that it may be quickly withdrawn from the machine at the completion of operation.

Slidably mounted in the machine, as shown in Figure 3, is a reciprocating plunger 23. Suitable means are provided for actuating this plunger from the main shaft, the same being herein shown as co-operat-

ing beveled gears 24 and 25; the latter being mounted upon a shaft 26 suitably journaled in the frame, and carrying at its end opposite the gear 25, a crank arm 27 to which a connecting rod 28 is attached. The connecting rod 28 is attached at its other end to a cross bar 29 which is fastened to the plunger 23 by means of a block 30 and collars 31. Through this connection the plunger 23 will be moved forward and back upon a single revolution of the main shaft. Referring to Figure 4 a second plunger 32 is mounted below the plunger 23 and carries at its end a punch 33. Suitable means are provided to actuate the plunger 32 simultaneously with the plunger 23, a block 34 connecting the two at their outer ends. The plunger 23 carries a hollow punch 35 with a sliding pin 36 pressed forward by a spring 37 which is mounted within the punch 35. A die plate 38 is rigidly attached to the machine and is provided with a hole 39 to co-operate with the punch 35 and a hole 40 to co-operate with the punch 33. A vertical channel 41 is formed by a guard plate 42 interposed between the die plate and the punches. Through this channel is drawn a strip of tape 43 from a supply roll 44, shown in Figures 1 and 2 as mounted upon a spindle 45 projecting from one of the standards of the machine.

Suitable means are provided to draw the tape step by step through the channel 41, the increments of movement corresponding to the distance between the axes of the punches 33 and 35 for a purpose which will hereafter appear. Tape feeding means are herein shown as a pair of co-operating feed rolls 46 and 47, shown diagrammatically in Figure 4, and also in Figures 2 and 3. Suitable means are provided to actuate the feed rolls, the same being herein shown as a cam operated ratchet and pawl mechanism. The upper feed roll is mounted upon a shaft 48 suitably journaled in bearings 100 which permit it to be pressed toward the co-operating feed roll 47 by set screws 49. This shaft also carries another feed roll which will be later referred to. A ratchet 50 (see Figure 13) is fast to the shaft 48 110 and a spring pressed pawl 51 is carried upon a pivoted arm 52 which is actuated through a link 53 by an arm 54 upon a vertically slidable standard 55 suitably journaled in the bed-plate of the machine and held in lowered position by a spring 56. The arm 54 carries a roller 57 which rides upon a cam 58 fast to the main shaft 3. The cam is so placed upon the shaft that the feed rollers will be actuated to move 120 the tape forward when the punches are free therefrom.

Suitable means are provided for feeding an eyelet so that it may be picked up by the pin 36, Figure 4, in the plunger 35 and car- 130

ried forward, passed through a hole in the washer and thereafter upset against the anvil 21 to fasten the washer to the envelope body. Such means are herein shown 5 as follows: Referring to Figure 1 a suitable eyelet selector box 60 is mounted upon a shaft 61 journalled in suitable bearings above the machine. The eyelet box, shown in more detail in Figure 12, may be of any 10 suitable construction adapted to deliver eyelets to a channeled gutter leading to the eyelet upsetting mechanism. The box is rotated from the main shaft through belts 62 and 63 running over pulleys 64, 65, 66 and 67. 15 The eyelet box delivers eyelets to the gutter 70 and the eyelets will slide down the gutter until they reach an escapement mechanism, shown in Figures 7, 8 and 9. This escapement mechanism is adapted to 20 release the eyelets one at a time and permit the released eyelet to fall to the bottom of the gutter where it is in position for engagement by the upsetting mechanism. Referring particularly to Figures 7, 8 and 9 25 it will be seen that the escapement mechanism comprises a reciprocatory member 71 having two knife edges 72 and 73 staggered in relation to the gutter. As shown in Figure 7 the eyelets are intended to pile up 30 and be caught upon the upper knife edge 72. Upon a reciprocation of the member 71 to the right, the knife edge 72 will release an eyelet from the column of eyelets and permit it to drop against the knife edge 35 73. Upon the reverse reciprocation to the left, knife edge 72 will pass between the eyelet resting upon 73 and the one above it while 73 will pass out of the way and permit the lowermost eyelet to drop. 40 The escapement slide 71 is actuated by the bell crank lever 74 having connection through a link 75 with an arm 76 carried by the feed roll actuating arm 54. Thus when the feed roll is actuated to move 45 the strip forward, the eyelet escapement mechanism will be actuated to drop a single eyelet down the chute. 50 The lower end of the gutter is formed in a pair of doors or gates, one of these gates 55 77 being shown in Figure 4 pivoted at 78 and held in normally closed position by a spring surrounding pivot. The eyelet sliding down the gutter from the escapement mechanism is stopped and held in alignment with the pin 36. 60 The operation of the mechanism just described in applying the fastening washer to the body of the envelope will be briefly described before the description of the remaining parts of the machine is taken up. 65 The tape 43 being in position, each reciprocation of the punch 33 will form a small hole therein. Assuming that this hole has been made and the tape moved forward one step so that the small hole in the tape is aligned with the center of the punch 35, the operation of this portion of the mechanism will be as follows: An envelope having been inserted over the shoe 20, the treadle 15 may be depressed to release the clutch and cause the rotation of the main shaft. This moves the punches 35 and 33 forward and the first result to be noted is that the pin 36 will pass through the eyelet which is in position at the bottom of the gutter. Then 75 the forward end of the punch 35 will open the gates 77 and the pin will pass through the small hole in the tape 43 until the end of the pin contacts with the envelope body and presses against the anvil 21. The 80 plunger 35 will move forward until it contacts with the tape 43 and forces it against the aperture in the die plate 38 whereupon a portion of the tape will be punched out to form a washer, supported by the pin 36, 85 which as the punch proceeds is being pressed back against the spring 37. The washer thus formed is carried forward by the punch and pin and positioned against the envelope body. Finally the eyelet will 90 be forced through the hole in the washer and through the material of the envelope and upset against the anvil 21. At the same time another small hole has been formed in the tape 43 by the punch 33. The eyelet 95 having been upset the punches will be retracted and as soon as they have cleared the die plate 38 the cam 58 may actuate the feed mechanism to move the tape forward one step. As soon as the gates 77 have 100 closed behind the punch 35, the eyelet escapement mechanism may be actuated to drop another eyelet into position; thus completing a single cycle of operation of this 105 part of the apparatus. 110 Proceeding with the description of the mechanism, the means for forming and affixing a reinforcing washer to the flap of the envelope is best shown in Figure 5 and its relative location to the mechanism just described is best known in Figure 3. Referring to Figure 5, a reciprocating plunger 80 is suitably mounted in the bed of the machine and is adapted to be actuated in unison with the plunger 23. It is connected to the cross bar 29 by a block 81 as shown in Figure 3. Just below the plunger 80 is a plunger 82 also fastened in the block 81. The end of the plunger 80 forms a punch which co-operates with a hole 83 in a die 115 plate 84 and the plunger carries an upsetting anvil 85. The plunger 82 carries a punch 86 to co-operate with a hole 87 in the die plate 84. A channel 88 Fig. 5 is formed between the die plate 84 and the two punches 120 and through this channel is passed a strip of reinforcing washer material 89. This strip is drawn from a supply roll 89' (Fig. 1) mounted upon a spindle 89" projecting from one of the standards 2 and is 130

led up over a guide roll 90 and between feed rolls 91 and 92; the feed roll 91 being mounted upon the same shaft 48 which carries the feed roll 46 and the feed roll 92 being mounted upon a shaft 93 upon which the feed roll 47 is also mounted. The feed roll 91 is rotated with feed roll 46 and the tape 89 is moved forward step by step as is the tape 43. Thus at each reciprocation of the block 81 the punch 86 will form a small hole in the tape and the punch 85 will cut out a portion of the tape to form a washer and carry it forward for a purpose which will appear later.

15 Aligned with the plunger 80 is a cooperating reciprocating plunger 100 slidably mounted in the frame of the machine. Just beneath the plunger 100 is a smaller plunger 101 corresponding to the plunger 82. These two plungers are actuated from the main shaft 3 through beveled gears 102 and 103 best shown in Figure 3. The bevel 103 is mounted upon a shaft 104 suitably journaled in the frame of the machine and this shaft carries a crank arm 105 which is connected by a connecting rod 106 with a block 107 secured to the plunger 100. The plunger 101 is suitably connected with the plunger 100. At each revolution of the main shaft 30 the plungers 100 and 101 are moved forward and back as in the case of the other plungers.

35 The end of the plunger 100 forms a punch 109 while the end of the plunger 101 carries a punch 110. A die plate 111 is rigidly mounted upon the machine and is provided with a hole 112 to cooperate with the punch 109. It is also provided with a smaller hole 113 to cooperate with the punch 110. Between the die plate 111 and the ends of the plungers is a guide plate 114 which forms a channel 115 through which a strip of tape 116 is drawn by suitable feed rolls.

40 Within the punch 109 is a pin or rod 117 which is free to slide therein and is pressed normally outward by a spring 118. This spring is best shown in Figure 6 which is a horizontal section through the center line of the plunger 100. It is desired to have the pin 117 projected from the punch 109 at the beginning of the cycle of operation of the machine for purposes which will hereinafter appear. Suitable means are therefore provided to release the pin upon the start of operation; the same being herein shown as a trigger mechanism best illustrated in Figure 6. Attached to a fixed abutment is an arm 119 pivoted at 120 and free to rotate only in a clockwise direction on the pivot from the position shown. Pivoted at 121 within the plunger is a trigger 122 which has an outwardly projecting arm 123 carrying an up-standing pin 124. The plunger 100 is shown in its completely retracted position in Figure 6. Upon forward movement of the plunger the pin 124 will contact with a cam surface 125 of a cam plate 126 fastened to the underside of the arm 119. The arm being restrained from movement toward the punch, the trigger will be drawn away from the enlarged end of the pin 117 and the pin will be released and shot forward by the spring 118. As the plunger moves forward the pin 124 will move along the cam plate 126 until the arm 123 contacts with a spring 127 which tends to hold the arm 119 in the position shown. At this time the end of the pin 117 will have come in contact with the advancing anvil 85 on the plunger 80 and be held from further forward movement so that the relative movement of the pin 117 with respect to the plunger 100 will be toward the right to compress the spring 118. Therefore as the plunger progresses further toward the left, the trigger 122 will bear against the enlarged end of the pin 117 and finally snap behind the enlarged end so that the relative position of the plunger, pin and trigger will be the same as that shown in Figure 6. At about this time the plunger will be retracted from its advanced position and the pin 124 on the trigger arm will pass under the arm 119 and contact with the cam surface 128 on the cam plate 126. The arm 119 will be rotated slightly in a clockwise direction during the retractile movement of the plunger until the parts come substantially into the position shown in Figure 6 when the arm 119, urged by the spring 127 will snap back into the position shown.

50 Means are provided for drawing the tape 116 through the channel 115 and are substantially similar to corresponding means acting upon the other tapes. The tape roll 130 (Fig. 1) is supported upon a spindle 131 attached to one of the standards of the machine and the tape is drawn from this roll through the channel, over a guide roll 132 and between feeding rolls 133 and 134. The feed roll 133 is mounted upon a shaft 135 which is journaled in sliding bearings so that the feed rolls may be brought together by set screws 136.

55 As in the case of feed rolls 91 and 46, suitable means are provided for intermittently rotating the feed roll 133 to feed the tape step by step. A ratchet 137 is fast to the shaft 135 and a spring pressed pawl 138 mounted upon an arm 139 is actuated through a suitable link connection 140 from an arm 141 carried by a suitable standard. The arm 141 has a roller 143 contacting with a cam 144 upon the main shaft 3 and the roller is maintained in contact with the cam by a spring 145. Eyelet feeding means substantially like that described in connection with the punch 35 are utilized to position an eyelet in front of the punch 109. The eyelet feed box 150 is driven through belts 151 and 62 the former running over pul-

125 130

leys 152 and 153. A gutter 154 leads from the eyelet box to the hinged gates 155 which position the eyelet at the axis of the pin 117.

An escapement mechanism similar to that 5 operating upon the eyelets in the gutter 70 is provided to operate upon eyelets in the gutter 154. An escapement bar 156 is shown in Figure 15 and the link connections 157 to an arm 158 upon the arm 141.

10 The operation of the parts just described may be understood from Figure 5. First with respect to the anvil carrying plunger 80. It will be observed that upon reciprocation this plunger will move toward the 15 tape 89; the anvil pin passing through a hole in the tape which has been punched at the previous operation by the punch 86. The end of the plunger 80 coming into contact with the tape will punch out a 20 portion of the tape to form a washer and carry it forward.

Upon the other side, the initial movement of the plunger 100 will operate to release the pin 117 which will be moved forward, 25 passed through an eyelet, which is positioned in front of it, through a hole in the tape 116 which has been punched in the previous operation by the punch 110 and will come in contact with the anvil pin 85 30 before the plunger 100 has travelled very far. During further forward movement of the plunger 100 the string feeding means, which are about to be described, may operate. Upon further movement the punch 35 109 will open the gates 155, pass the guide 114 and contact with the tape 116, cutting out a portion to form a washer and carrying the eyelet and washer forward to the central position. The plungers 80 and 100 thus 40 form the washers or buttons and position them against opposite sides of the flap or blank, and the actuation of the plungers not only forms the washers and positions them against the envelope, but also sets the eyelet 45 which serves as a fastener by which the washers are affixed to the envelope flap. The description of the completion of the operation will be reserved until the string feeding means has been described.

50 The attachment of the string to the flap of the envelope is preferably effected by looping the string around the pin 117 before the dies have been brought together to upset the eyelet. Thus the string is looped in 55 position to be fastened between the upset flanges of the eyelet. It will readily be observed how this is effected while the reinforcing washer is being formed by the punch 85, and the fastening washer is being formed 60 by the punch 109. After the envelope flap has been placed alongside the die plate 84 and the treadle 15 depressed, the initial movement of the plunger 100 will release the pin 117 and permit it to shoot forward into 65 contact with the envelope flap. Then, while

the punches are coming together the string may be wound upon the pin and thereafter caught between the envelope flap and the reinforcing washer and firmly held there by the flanges of the eyelet.

70

Means for accomplishing this result are herein shown as a hollow gear 200 mounted within a suitable housing and rotating concentrically about the pin 117 and of sufficient size to permit the punch 109 to pass 75 therethrough. This gear is rotated from the main shaft 3 by a suitable train of gearing comprising the gears 201, 202 and 203, and is preferably rotated at a greater speed than the main shaft. In this instance the 80 gear 200 which, with its associated parts, will hereinafter be termed the "looper" makes four revolutions to one revolution of the main shaft. Means are provided on the gear to grasp the end of a string which is 85 presented to the looper by means herein-after described, the string grasping means being herein shown as a substantially U-shaped member 204, Figure 20, normally 90 spring pressed against the face of the gear but adapted to be extended from the face of the gear at the proper moment in the operation of the machine when it is desired to grasp a piece of string presented thereto. This U-shaped member 204 extends through 95 the gear and is fixed to a ring 205 having a cam surface 206. The construction of this looper will be more readily seen from Figures 19, 20 and 21 which are respectively 100 an end view, front view and cross-section of the looper. The ring 205 is normally held away from the gear by springs 207 and its movement is limited by the string 105 engaging member 204. Thus, it will be seen that when an end of a string is placed under the member 204, it will be firmly grasped between this member 204 and the face of the gear in the absence of any control thereof by the ring 205 with its cam surface 206.

110 Means may be provided to control the opening and closing of the member 204 for the purpose of threading the string thereunder, the said means being herein shown as a cam 208 mounted upon a lever 209 and controlled by a cam 210 upon the main shaft 115 (see Figure 15). As this particular mechanism is designed to operate, it is desirable to have the looper opened for grasping the string once in its four revolutions, that is, at a time when the pin 117 is extended. It will therefore be seen that when the cam 208 is brought to the position shown in Figure 15, the looper, rotating in a counter-clockwise direction will be opened by the 120 cam 208 for threading the string. As the looper continues to rotate the high point of the cam surface 206 is rotated past the cam 208 and the string engaging member 204 125 will grasp the string end which has been presented to it and will wind the string 130

about the pin 117 until the string is released or withdrawn from the looper.

By the described arrangement the string is formed to present a complete loop about 5 the rivet shank which insures an effective securing of the string to the envelope. This connection is substantially stronger than in the case of a loop open at one side, partly because of the greater arc of contact between the string and the parts between which it is clamped and partly because the string is crossed in the narrow space between the button and envelope and therefore more tightly secured.

15 Means may be provided to present the end of a string to the looper mechanism so that it may be engaged by the member 204 and the rim of the gear 200, the same being herein shown as a reciprocating string carrying member 215 and its associated parts. This string carrying member is provided with a finger 216 having a resilient side plate 217 to engage the string when it is threaded therethrough and to tension the 25 string during the succeeding operations. The string carrying member 215 is mounted in a guideway 218 and is reciprocated by a crank arm 219 and link 220, the crank arm being mounted upon a shaft 221 which in 30 this particular instance, is driven in synchronism with the main shaft 3 through a train of gears 222-227.

Means may be provided to sever the string, the same being herein shown as shears 230 having a fixed blade 231 and movable blade 232 and mounted upon an oscillating member 233 pivoted at 234 upon the guideway. The two blades of the shears are pivoted at 235 and are held in operative relation by 40 any suitable means herein shown as a stud and spring 236. Suitable means may be provided to bring the shears into position for cutting the string, the same being herein shown as a cam 237 upon the oscillating 45 shears mounting 233 adapted to be engaged by an anti-friction roller 238 upon the string carrying member 215 to oscillate the shears and bring them into operative position for cutting the string. The shears mounting is 50 shown in its normal position in Figures 15 and 17 and is yieldingly held in this position by a spring 239 attached to the shears mounting and to an arm 240 which in turn is rigidly attached to the guideway 218.

55 Means may be provided to operate the shears to cause them to cut the string upon their being brought forward through the aperture 241 in the guideway, such means being herein shown as an anti-friction roller 242 upon the rearwardly extending movable blade 232 of the shears. (See Figures 17 and 18). This roller 242 is adapted to be engaged by a pair of cams 243 and 244 which cause the shears to close and open respectively. It will be observed, that when the shears

mounting is oscillated upon the pivot 234 the shears will be swung forward until the anti-friction roller 242 contacts with the cam 243. Upon further forward movement of the shears the cam 243 will operate to bring 70 the cutting edges of the shears together and thereupon the machine being so organized as to bring the string between these cutting edges, the string will be severed just above the threader. As the string carrying member 75 is moved upward by the crank and link connection with the shaft 221 the roller 238 upon the string carrying member will be released from engagement with the cam 237 upon the shears mounting and allow the 80 same to resume its normal position under the action of the spring 239. The rearward movement of the shears will bring the shears operating roller 242 in contact with the cam 244 which will cause the shears to be opened 85 in readiness for the next forward movement preceding the cutting of the next length of string.

To assist in properly locating the envelope an adjustable table 250 is positioned in 90 front of the machine and supported in a bracket 251 as shown in Figures 1 and 2. This table may be raised or lowered by means of a screw 252 which can be rotated by a handle 253. The screw is threaded in 95 a bracket 254. The table may be adjusted to a proper horizontal plane by another screw 255 shown in Figure 2.

The operation of the machine as a whole 100 may be summarized as follows: Starting with the several parts of the apparatus in the positions shown in Figures 1, 2, 4 and 5, and referring particularly to those figures, an envelope to which the string closure is to be affixed may be inserted in the machine 105 by extending the flap into the space between the die plate 84 and the looper 200; the shoe 20 being inserted in the envelope so that the body of the envelope comes between the shoe 20 and the die plate 84. The table 250 will 110 of course be previously adjusted to position the envelope properly. The envelope being in place the treadle 15 may be depressed to release the clutch mechanism and start the rotation of the main shaft 3. The several 115 plungers will start their forward movement at a relative speed depending upon the distance which they have to travel. The initial movement of the plunger 100 will release the pin 117 and shoot it forward into contact with the envelope flap. The initial rotation of the string looper will cause it to grasp the string and wind the string about the pin while the several plungers are coming forward. In operation this action results in winding the string about the eyelet to be secured by the latter. When the main shaft has made substantially one quarter revolution the several punches will have 120 reached their respective tapes and cut out 125 130

washers therefrom. In the case of the plunger 100 the punch will carry forward an eyelet and washer upon the pin 117, while the plunger 80 cuts out and carries forward 5 a reinforcing washer on the anvil pin 85, and the punch 35 cuts out and carries forward a washer and eyelet upon the pin 36. When the main shaft has completed about the first half of its revolution, the punch 35 10 will have a washer and eyelet in contact with the body of the envelope, the anvil 85 will hold the reinforcing washer in contact with the inside of the flap of the envelope and the punch 109 will hold a fastening washer and 15 eyelet in contact with the outside of the flap of the envelope, while the string will be wound upon the pin 117 and when the eyelet on the pin has advanced far enough the string will ride up upon the shank of the 20 eyelet. During this time the string carrier 215 will have descended in its guideway until the roller 238 is nearly in contact with the cam 235 of the shears mechanism. At the completion of the first half revolution 25 the punch 35 will force the eyelet carried by it through the paper of the body of the envelope and upset it against the anvil thus securing the fastening washer to the body of the envelope, while the cooperating plungers 80 and 100 will force an eyelet through 30 the fastening and reinforcing washers and the flap of the envelope and upset it to secure the washers and string firmly thereto. At substantially this time the shears will be 35 moved forward to cut the string at the proper point.

During the second half revolution of the main shaft the several plungers will be retracted to their starting positions, the tapes 40 advanced one step and an eyelet dropped to the bottom of each gutter, and the string carrier will have returned to the position of Figure 5 to place an end of the string where it can be grasped by the looper. This completes a single cycle of operation and places the machine in position for its next operation.

It will be understood that it is not indispensable that the several parts of the machine be used in combination as their separate advantages may accrue from their independent use in any suitable machine, and it is to be understood that the invention may be variously modified and embodied 55 within the scope of the subjoined claims.

I claim as my invention:

1. In a machine of the character described, the combination of means to position a button upon one side of a flap of an envelope; 60 means to position a reinforcing washer upon the other side of the flap; means to feed a fastener thereto; means to position a button upon the body of the envelope; means to feed a fastener thereto; and means to actuate 65 the positioning means to affix the buttons

and reinforcing washer simultaneously by the fasteners.

2. In a machine of the character described, the combination of means to position a button upon one side of a flap of an envelope; 70 means to position a reinforcing washer upon the other side of the flap; means to feed a fastener thereto; means to position a string for fastening to the flap of the envelope; means to position a button upon the body of the envelope; means to feed a fastener thereto; and means to actuate the positioning means to affix the buttons and 75 reinforcing washer simultaneously by the fasteners. 80

3. In a machine of the character described, in combination, means to position a button upon one side of the flap of an envelope; means to position a reinforcing washer upon the other side of the flap; means to position a button upon the body of the envelope; 85 and means to affix the buttons and the washer to the flap and body of the envelope by fasteners.

4. In a machine of the character described, the combination of means to affix a button to one side of the flap of an envelope; oppositely acting means to affix a reinforcing washer to the other side of the flap of an envelope; means to affix a button to the body 95 of an envelope; and means to actuate said button and washer affixing means simultaneously.

5. In a machine of the character described for applying fastener devices to an article 100 in predetermined cooperative relation, in combination, means for positioning a button against the article and setting a fastener through the button and the article, means for positioning a second button against the article and setting a fastener through it and the article, means for feeding a flexible element into position to be secured to the article by one of said fasteners, and means for actuating the button positioning and fastener setting means to simultaneously set both fasteners. 105

6. In a machine of the character described, the combination of a button forming punch having an eyelet carrying member; means to position an end of string adjacent said eyelet carrying member; means to feed an eyelet to said eyelet carrying member; an upsetting anvil; and means to actuate said punch to form a button and to affix it together with the string end to a sheet of material by the eyelet. 110

7. In a machine of the character described, in combination, means to position a reinforcement against the flap of an envelope, 125 means for setting an eyelet through the reinforcement and envelope flap, means for setting a fastener through the body of the envelope and means for simultaneously operating both setting means. 130

8. In a machine of the character described, in combination, means to position a button upon one side of the flap of an envelope; means to position a button upon the body 5 of the envelope; and means to affix the buttons to the flap and body simultaneously.
9. In a machine of the character described, the combination of means to affix a button to one side of the flap of an envelope, means 10 to affix a washer to the opposite side of the flap of an envelope, means to affix a button to the body of the envelope, means to feed a string to position to be affixed under one of the buttons and means to actuate both 15 button affixing means and the washer affixing means simultaneously.
10. In a machine of the character described, the combination of means to affix a button to one side of the flap of an envelope, means 20 to affix a button to the body of the envelope, means to feed a string to position to be affixed under one of the buttons and means to actuate both button affixing means simultaneously.
11. In a machine of the character described, the combination with a horn having an anvil arranged to enter the open end of an envelope placed thereon of means for setting a fastener through a part of the envelope body against the anvil on one side of the horn, and means for setting a cooperating fastener through the flap on the opposite side of the horn.
12. In a machine of the character described, the combination with a horn arranged to enter the open end of an envelope of fastener setting devices operable simultaneously to set fasteners one through the body and one through the flap of the envelope.
13. In a machine of the character described, the combination of eyelet setting means; means to feed an eyelet thereto; and means to loop a string in position to be fastened between the upset flanges of an eyelet.
14. In a machine of the character described, the combination of eyelet setting means; means to feed an eyelet thereto; means to position a button between the cooperating parts of the eyelet setting means; means to loop a string in position to be retained by an eyelet; and means to actuate the eyelet setting means to affix the button and string to an interposed sheet of material by the eyelet.
15. In a machine of the character described, the combination of eyelet setting means; means to feed an eyelet thereto; means to loop a string in position to be retained by an eyelet; and means to sever a predetermined length of string.
16. In a machine of the character described, the combination of eyelet setting means; means to feed a button between the cooperating parts of the eyelet setting means; means to loop a string in position to be fastened under the upset flanges of an eyelet; means to sever a predetermined length of string; and means to actuate the eyelet setting means to affix the button and string to an interposed sheet of material by the eyelet.
17. In a machine of the character described, the combination of eyelet setting means including a button forming punch having a spring pressed pin; and string looping means to loop a string about the pin.
18. A machine of the character described, comprising in combination, an eyelet setting plunger; a pin axially mounted with respect to said plunger, said pin being movable with respect to said plunger; means to position an eyelet in the path of the pin; means to pass the pin through the eyelet; and means to wind a string upon the pin for fastening under the upset flanges of an eyelet.
19. In a machine of the character described, the combination of means to position a button upon one side of a flap of an envelope; means to position a reinforcing washer upon the other side of the flap; means to feed a fastener thereto; means to loop a string in position for attachment by the fastener; means to position a button upon the body of the envelope; means to feed a fastener thereto; and means to actuate the positioning means to affix the buttons, spring and reinforcing washer simultaneously by the fasteners.
20. In a machine of the character described, the combination of a reciprocable washer forming punch carrying an eyelet set; an opposed button forming punch carrying a cooperating eyelet set; means to position an eyelet to be carried forward by one of said opposed punches; means to position an end of string for fastening under the upset flanges of an eyelet; and means to actuate said opposed punches to affix the washer and button to opposite sides of an interposed sheet material by upsetting the eyelet.
21. In a machine of the class described, the combination with a washer feeding device, an eyelet feeding device, and a string feeding device, of means for cutting said string, means for cutting the washer and upsetting the eyelet, and means for simultaneously operating all of said devices and said means from a single source of power.
22. In a machine of the class described, the combination with means for receiving an envelope, of means for puncturing the flap of said envelope and inserting therethrough an eyelet, means for supplying a washer to each side of said flap, means for winding the end of a string about said eyelet; and means for upsetting said eyelet to clamp said washers, said string and said envelope flap.

23. In a machine of the class described, the combination with means for receiving an envelope, of means for puncturing the flap of said envelope and inserting there-through an eyelet, means for supplying washers to opposite sides of said flap, means for winding the end of a string about said eyelet, and means for upsetting said eyelet to clamp said washers, said string and said envelope flap, and means for cutting a pre-determined length of said spring.
24. In a machine of the character described the combination of fastener setting means, means to form a button and to position it to be affixed by the fastener, means to form a string into a loop about the fastener and means to actuate the fastener setting means to affix the button and string to an interposed sheet of material by the fastener.
25. In a machine of the class described, the combination with a main shaft, and envelope positioning mechanism, for positioning an envelope in the machine with the flap thereof extended, of washer feeding devices for feeding washer material to opposite sides of said flap, an eyelet feeding device for feeding an eyelet to one side of said flap, cutting and upsetting devices for cutting washers from said material on opposite sides of said envelope flap, and upsetting said eyelet, a string feeding device, a string winding device for winding said string around said eyelet, a string cutting device for cutting predetermined lengths of said strings, and means for actuating all of said devices from said shaft.
26. In a machine of the class described, the combination with a main shaft, and an envelope positioning mechanism, of a washer feeding device for feeding washer material to said envelope, an eyelet feeding device for feeding eyelets to said envelope, a cutting and upsetting device, for cutting a washer from said material and upsetting an eyelet, a string feeding device, a string winding device, for winding said string around said eyelet, a string cutting device for cutting predetermined lengths of said string, and means for actuating all of said devices from said shaft.
27. In a machine of the class described, the combination with a main shaft, and an envelope positioning mechanism, for positioning an envelope in the machine with the flap thereof extended, of washer feeding devices for feeding washer material to opposite sides of said flap, and to one side of the body of said envelope, eyelet feeding devices for feeding an eyelet to said flap and another eyelet to one side of the body of said envelope, cutting and upsetting devices for cutting out washers from said material on opposite sides of said envelope flap, and on one side of the envelope body, and for upsetting said eyelets, a string feeding device, a string winding device for winding said string around one of the eyelets, a string cutting device for cutting predetermined lengths of said string, and means for actuating all of said devices from said shaft.
28. In a machine of the class described, an eyelet positioning device, a string feeding device, and means for winding said string about the eyelet positioned in said eyelet positioning device.
29. In a machine of the class described, an eyelet positioning device, a string feeding device, a rotatable member mounted to rotate about the eyelet positioning device comprising a rigid member and a yielding member, means for momentarily actuating said yielding member against tension to create a space between said yielding member and the rigid member.
30. In a machine of the character described, the combination of means to position a button upon the flap of an envelope; means to feed a fastener thereto; means to position a button upon the body of the envelope; means to feed a fastener thereto; and means to actuate the positioning means to affix the buttons by the fasteners.
31. In a machine of the character described, the combination of means to position a button upon the flap of an envelope; means to feed a fastener thereto; means to position a string for fastening to the flap of the envelope; means to position a button upon the body of the envelope; means to feed a fastener thereto; and means to actuate the positioning means to affix the buttons and string by the fasteners.
32. In a machine of the character described, the combination of means to position a button upon the flap of an envelope; means to feed a fastener thereto; means to position a button upon the body of the envelope; means to feed a fastener thereto; means to position a string for fastening to the envelope adjacent one of said buttons; and means to actuate the positioning means to affix the buttons and string by the fasteners.
33. In a machine for applying to the flap and body of an envelope, on one a string and on the other a button with which the string is to cooperate in fastening the envelope in closed position, means for applying both said string and button, comprising in combination a string-applying and fastening mechanism so located as to apply the string to one part of the envelope, a button applying and fastening mechanism so located with relation to the other as to apply the button to the other part of the envelope, and cooperating means for actuating both of said applying and fastening mechanism.
34. In a machine for applying to the flap and body of an envelope, on one a string

- and on the other a button with which the string is to cooperate in fastening the flap in closed position, means for applying both said string and button with a single positioning of the envelope, comprising in combination a string-applying and fastening mechanism so located as to apply the string to one part of the envelope, a button applying and fastening mechanism so located 10 with relation to the other as to apply the button to the other part of the envelope, and cooperating means for actuating both of said applying and fastening mechanism.
35. In a machine such as set forth in claim 15 33, the string applying and fastening mechanism comprising means for applying and fastening a button simultaneously with said string.
36. In a machine such as set forth in claim 20 35, the string and button applying and fastening mechanism comprising means for applying an eyelet and for fastening the string and button by upsetting said eyelet.
37. In a machine such as set forth in claim 25 33, mechanism, cooperating with the string applying and fastening mechanism for severing said string.
38. In a machine such as set forth in claim 30 33, mechanism cooperating therewith, for applying and fastening a reinforcing piece to the opposite side of that portion of the envelope to which the string is applied.
39. In a machine of the character described for fastening string to a blank by 35 means of an eyelet, the combination with opposed relatively movable eyelet sets and automatic means for supplying eyelets thereto of means for forming a string into a complete loop coaxial with the eyelet sets and 40 means to operate said sets to affix an eyelet and to operate the loop forming means in such timed relation that the loop of string will surround and be secured to the blank by the eyelet.
40. In a machine for affixing string to a blank by means of an eyelet, the combination with means for periodically feeding a fastening washer and eyelet, positioning the same in axial alignment and passing the 50 eyelet through the fastening washer and the blank to secure the washer to the blank, of means for forming a complete loop in the string coaxial with the washer and eyelet and positioning the same in a plane between the washer and blank, and means for operating said first mentioned means and said 55 loop forming and positioning means in timed relation to secure the loop to the blank and between it and the washer.
41. In a machine for affixing string to a blank by means of an eyelet and a fastening washer the combination with mechanism for setting an eyelet in a blank and mechanism for automatically supplying a fastening 60 washer in position to be secured to the blank by the eyelet of means cooperating with said mechanism for forming a string into a loop about the eyelet to be secured to the blank by the washer and eyelet.
42. In a machine of the character described for securing a string to a blank, the combination with automatic mechanism for feeding eyelets, automatic mechanism for supplying and positioning buttons against blanks, inserting eyelets through both the 70 buttons and blanks and clenching them, of looping mechanism for forming a string into a loop coaxial with a button and an eyelet and between the button and blank and means to operate said mechanisms in timed relation 75 such that the loop will be formed after the blank is positioned in the machine and the button and eyelet are brought into axial alignment, but before the blank with the button and eyelet applied is removed from the machine.
43. In a machine of the character described, the combination with automatic fastener feeding mechanism and means for applying a fastener to a blank, of means 80 cooperating with the applying means for looping a string entirely around the fastener previous to the completion of the applying operation and thereby attach the string to the blank.
44. In a machine for securing a length of string to a blank, the combination with automatic eyelet feeding means and eyelet sets 85 relatively reciprocable to affix an eyelet to a blank, of a rotatable looper concentric with the axis of the sets, the sets and looper cooperating to affix a string to a blank by means of an eyelet.
45. In a machine for securing a string to a blank, the combination with means for supplying and positioning a button and feeding and setting a fastener to secure said button to a blank, of means cooperating with said 90 first mentioned means to cause a string to encircle the fastener, said two means 95 cooperating to secure a string to a blank between the button and the blank.
46. In a machine of the character described, the combination with automatic mechanism for supplying eyelets one by one 100 and an eyelet setting device, of a loop forming mechanism comprising a rotatable element having string engaging means and means to rotate said element through substantially a complete circle to form the 105 string into a loop in position to be secured between the flanges of the eyelet.
47. In a machine of the character described the combination with automatic eyelet feeding means and eyelet sets for securing a button to a blank of means for forming a loop coaxial with the eyelet sets and positioning the loop at the time it is formed in a plane parallel to and between the button and blank.

48. In a machine of the character described the combination with automatic eyelet feeding means and eyelet sets for securing a button to a blank by means of an eyelet, of an annular rotatable looper through which one eyelet set passes, arranged to engage a string during its rotation to form a loop therein said sets and looper cooperating to secure the string to the blank between the button and said blank.
49. In a machine of the character described, the combination with an eyelet magazine and means for feeding eyelets therefrom and eyelet sets for securing an eyelet to a blank, of a loop forming device comprising an annular member rotatable about the axis of the sets and having string engaging means arranged to wind the string into a loop.
50. In a machine of the character described, the combination with an eyelet magazine, means for feeding eyelets therefrom and eyelet sets for securing an eyelet to a blank, of a loop forming device comprising an annular member rotatable coaxially with the eyelet sets having a string gripping element.
51. In a machine of the character described for securing a string to a blank, the combination with automatic mechanism for feeding eyelets one by one, and automatic mechanism for supplying and positioning buttons against blanks and securing said buttons to the blanks by means of the eyelets including opposed relatively movable eyelet sets of an annulus arranged to control a string and having an open center larger than one of the sets and coaxial therewith to permit the set to project therethrough, said annulus being provided exteriorly with gear teeth, together with gearing engaging said teeth and driving the annulus.
52. In a machine of the class described, eyelet setting means for securing a circular disk or washer to the body portion of an envelope, and a second eyelet setting means for simultaneously securing a circular disk or washer to the seal flap of the envelope.
53. In a machine of the class described, a supporting bed, an anvil mounted on said bed, a second anvil on said supporting bed, said anvils being in position to engage with the seal flap and body portion of an envelope, and mechanism co-operating with each of said anvils for automatically securing disk and eyelet fastening means to the seal flap and body portion of an envelope.
54. In a machine of the class described, a supporting bed having a nose adapted to project within the open end of an envelope, the seal flap of the envelope resting on one side of said nose and the body portion of said envelope engaging the other side of the nose, an anvil on the supporting bed adapted to engage with the seal flap of the envelope,
- a second anvil mounted upon the supporting bed and adapted to engage with the body portion of the envelope, means for feeding a circular disk or washer to a point adjacent said first anvil and adjacent the seal flap of the envelope, eyelet setting means for securing said disk to said seal flap, means for feeding a circular disk or washer to a position adjacent the second anvil and on one side of the body portion of the envelope, and eyelet-setting means for securing said disk to the body portion of the envelope.
55. In a machine of the character described, the combination of parallel button forming and eyelet setting plungers, mechanism for feeding a strip of washer material past each plunger, an eyelet feeding mechanism for feeding eyelets to each plunger, a rotatable annular looper through which one of said plungers operates, a die through which each plunger operates and with which it cooperates to cut a washer from the strip of material, an anvil arranged to co-operate with each plunger and actuating mechanism for simultaneously actuating the plungers to cut a washer from each strip of material and affix the same to an interposed blank with a string looped around one of the eyelets beneath the washer.
56. In a machine of the character described for fastening string to a blank, in combination, means for forming a washer and positioning it against one side of the blank, means for inserting a fastener through the washer and blank, means for positioning a string between the washer and blank and means for actuating the washer forming and fastener inserting means to affix the washer and secure the string to the blank.
57. In a machine of the character described, in combination, means for forming and positioning a washer on one side of a sheet of material, an associated device for positioning a cooperating fastener in setting relation on the opposite side of said material, means for positioning a string to be engaged by the fastener, and means for actuating the forming and positioning means for setting the fastener.
58. In a machine of the character described fastener setting mechanism for securing a fastener to a blank, means for forming a washer in substantially fastener receiving position on each side of said blank, means for positioning a string between the washers, means for actuating the fastener setting and washer forming means to secure the washers and string to the blank by the fastener.
59. In a machine of the character described fastener setting mechanism for securing a fastener to a blank, means for forming a washer in substantially fastener receiving position on each side of said blank,

- means for positioning a string between the washers, means for actuating the fastener setting and washer forming means to secure the washers and string to the blank by the fastener.
60. In a machine of the character described, in combination, fastener setting mechanism for applying a fastener to a blank, means for forming a washer in substantially fastener receiving position on each side of said blank, means for feeding a fastener to the fastener setting mechanism, means for positioning a string to be engaged by the fastener, and means for actuating the fastener setting mechanism to secure the washers and string by the fastener.
61. In a machine of the character described, in combination, fastener setting mechanism for securing a fastener to a blank, means for forming two separate reinforcing washers in substantially fastener receiving position, means for feeding washer material to said forming means, means for placing a string in position to be engaged by the fastener, and means for actuating the fastener setting and washer forming means to secure the washers and string to a blank by the fastener.
62. In a machine of the character described, in combination, a reciprocating anvil, a reciprocating set, means for forming a washer in the path of the set, means for forming a washer in the path of the anvil, means for positioning a string between the washers, and means for actuating the anvil and set to secure the washers and string to a blank by a fastener.
63. In a machine of the character described, in combination, punches for cutting out washers, means for feeding strips of washer material to said punches, means to actuate said punches to cut out perforated washers, means for positioning a string between the washers, and means cooperating with said punches to affix said washers to a blank by a fastener.
64. In a machine of the character described, in combination, means to position a washer against one side of a blank, means to position a washer against the opposite side of the blank, means to feed a fastener thereto, means to feed a string adjacent the fastener, and means to actuate the positioning means to affix the washers and string by the fastener.
65. In a machine of the character described, in combination, means to position a washer against each side of a blank, means to feed a fastener thereto and to affix the washers to the blank by the fastener, and mechanism for actuating both positioning means and the affixing means while the blank is held in one substantially fixed position, together with means for placing a string in position to be secured to the blank by the washer and fastener.
66. In a machine of the character described for fastening string to a blank, in combination, means for forming a washer, and positioning it against one side of the blank comprising a die and a punch operating therethrough, means for inserting an eyelet from the opposite side through said blank and washer, means to position a string to be secured by the eyelet to the blank, and means for actuating the aforesaid means to affix the washer and string to the blank.
67. In a machine of the character described, the combination of opposed reciprocating washer forming and eyelet setting plungers, dies through which said plungers operate and with which they cooperate to cut washers from strips of washer material, means to feed washer material to one of said plungers, means to feed a string to position between the plungers, and means to actuate said plungers to form washers and affix them to opposite sides of an interposed blank by an eyelet with the string secured by one of the washers.
68. In a machine of the character described for fastening string to a blank by means of an eyelet, in combination, means for forming a washer and positioning it against one side of the blank, means for inserting an eyelet from the opposite side of the blank through the blank and washer, means for positioning a string between the washer and blank and means for actuating the washer forming and eyelet inserting means to affix the washer to the blank.
69. In a machine of the character described, in combination, means for forming and positioning an annular washer against one side of a blank, means cooperating with said first mentioned means for inserting an eyelet from the same side through the hole of said washer and through said blank, a device to feed a string adjacent the eyelet, an eyelet clinching anvil and means for actuating the aforesaid means and anvil to clinch the eyelet to secure the washer and string to the blank.
70. In a machine of the character described, in combination, means for forming and positioning a washer against one side of a blank comprising a die and a punch operating therethrough, means for inserting an eyelet from the opposite side through the said washer and blank, a device for positioning a string adjacent the eyelet, and means for actuating the aforesaid means to affix the washer and string to the blank by means of the eyelet.
71. In a machine of the character described, in combination, means for forming and positioning a washer against one side of a blank comprising a die and a punch

- operating therethrough, means cooperating with the punch for inserting an eyelet first through the washer and then through the blank, means for positioning a string adjacent the eyelet, and means cooperating with said punch for setting the eyelet. 5
72. In a machine of the character described, in combination, eyelet setting mechanism and washer forming mechanism comprising a punch and eyelet set having a diameter corresponding to the outside diameter of the washer and a second punch for punching a central hole in the washer, said punches being adapted to operate simultaneously upon a strip of washer material fed past the punches by successive steps, and means for positioning a string in the line of action of said eyelet setting and washer forming mechanism. 10
73. In a machine of the character described, in combination, means for guiding a blank, means for feeding a strip of material to one side of said blank and means for puncturing said strip at predetermined intervals as the same is fed through said machine, means for severing a punctured portion of said strip from the remainder thereof, means for inserting an eyelet first through the punctured portion of said severed strip and then through a portion of the blank, means for positioning a string to be engaged by said eyelet, and means for upsetting the said eyelet to clamp said portion of the strip said string and said blank together. 15
74. In a machine of the character described, in combination, means for positioning washers on opposite sides of a blank, means for positioning a string between the washers, means for feeding an eyelet and means to actuate the positioning means to affix the eyelet to the blank and washers. 20
75. In a machine of the character described, in combination, means for forming and positioning washers on opposite sides of a blank while said blank is held in predetermined position, means for feeding and setting an eyelet through the washers and blank while said blank is held in said predetermined position, and means for feeding a string in position to be secured to the envelope by the washers and eyelet. 25
76. In a machine of the character described, in combination, a reciprocable washer forming punch carrying an eyelet set, an opposed washer forming punch carrying a cooperating eyelet set, means to position an eyelet to be carried forward by one of said opposed punches, means for placing a string in position to be secured by the eyelet, and means to actuate the opposed punches to affix the washers to opposite sides of an interposed blank by upsetting the eyelet. 30
77. In a machine of the character de- 35
- scribed, in combination, a washer forming punch having an axially mounted longitudinally movable eyelet carrying member, an oppositely acting washer forming eyelet setting punch, means for positioning a string adjacent the eyelet, and means to actuate said punches to form washers and to affix the same to an interposed blank by said eyelet. 70
78. In a machine of the character de- 75
- scribed the combination of fastener setting means, means to feed a fastener thereto, means to form a button in position to be affixed by the fastener, means to form a string into a loop and means to actuate the fastener setting means to affix the button and string to an interposed sheet of material by the fastener with the string looped about the fastener. 80
79. In a machine of the character de- 85
- scribed the combination of fastener setting means, means to feed a button to position to be affixed by the fastener, means to loop a string around the fastener to be fastened thereby, means to sever a predetermined length of string and means to actuate the fastener setting means to affix the button and string to an interposed sheet of material by the fastener. 90
80. In a machine of the character de- 95
- scribed the combination of fastener setting means, means to feed a fastener thereto, means to feed a button to position to be affixed by the fastener, means to form a string into a loop and means to actuate the fastener setting means to affix the button and string to an interposed sheet of material by the fastener with the string looped about the fastener. 100
81. In a machine of the character de- 105
- scribed, the combination of fastener setting means, including opposed button forming punches; a string looping means; and means to actuate the fastener setting means and string looping means to form and affix buttons to opposite sides of an interposed blank by a fastener with the string looped around the fastener and secured thereby. 110
82. In a machine of the character de- 115
- scribed for fastening buttons and a string to a blank by means of a fastener, the combination of opposed plungers constituting washer forming punches and fastener sets, apertured die plates through which said punches operate and with which they cooperate to form washers, an annular rotatable string looper through which one of said plungers operates and means for operating said plungers and looper to form washers and to affix the washers and a string to a blank by a fastener. 120
83. In a machine of the character de- 125
- scribed, the combination with means for receiving a blank, of means for inserting a fastener through the blank, means for sup- 130

- plying a washer to each side of the blank, means for looping a string about the fastener and means for upsetting the fastener to clamp the washer and string to the blank.
- 5 84. In a machine of the character described, the combination of an eyelet setting plunger, a pin coaxial therewith, means to position an eyelet in the path of said pin, means to pass the pin through the eyelet, 10 and means to wind a string upon the pin for fastening under the upset flanges of the eyelet.
- 15 85. In a machine for securing a length of string to a blank, the combination with automatic eyelet feeding means and eyelet sets relatively reciprocable to affix an eyelet to a blank, of a rotatable looper concentric with the axis of the sets having string gripping means, the sets and looper cooperating 20 to affix a string to a blank by means of an eyelet.
- 25 86. In a machine of the character described for fastening a button and string to a blank by means of an eyelet, the combination with opposed eyelet sets of a die with which one of said eyelet sets cooperates to form a washer, of means for forming a string into a loop coaxial with the eyelet sets and means to cause relative movement 30 between the eyelet sets and die and to actuate the loop forming means in timed relation to form a washer and affix it and the string to a blank by an eyelet.
- 35 87. In a machine for affixing string to a blank by means of a fastener and a fastening washer the combination with mechanism for setting a fastener in a blank and mechanism for automatically forming and feeding a fastening washer into position to be secured to the blank by the fastener, of means cooperating with said mechanism for forming a string into a loop about the fastener to be secured to the blank by the washer and fastener.
- 40 88. In a machine of the character described, the combination with automatic eyelet feeding means and eyelet sets for securing a button to a blank by means of an eyelet, of an annular rotatable looper through which one eyelet set operates, arranged to grip a string during its rotation to form a loop therein, said sets and looper cooperating to secure the string to the blank between the button and said blank.
- 45 89. In a machine of the character described the combination of means for determining the position of a blank, means for forming and affixing a button to the blank, means for forming a string into a loop between the button and blank and means to actuate the button forming and affixing and the loop forming means in such timed relation that the string is formed into a loop and then affixed between the button and the blank.
- 55 90. In a machine of the character described, the combination of fastener setting means, means to feed a fastener thereto, means to form a string into a complete loop in position to be retained by the fastener, 70 and means to sever a predetermined length of string.
- 10 91. In a machine of the character described, the combination of fastener setting means, means to feed a fastener thereto, 75 means to form a string into a loop in position to partially surround and be retained by the fastener, and means to sever a predetermined length of string.
- 15 92. In a machine of the character described, the combination of fastener setting means, means to feed a fastener thereto, means to form a button in position to be affixed by the fastener, means to form a string into a complete loop about the fastener and 80 means to actuate the several aforesaid means to affix the button and string to an interposed blank.
- 20 93. In a machine of the character described the combination of fastener setting 90 means, means to feed a button to position to be affixed by the fastener, means to loop a string completely around the fastener to be fastened thereby, means to sever a predetermined length of string, and means to 95 actuate the fastener setting means to affix the button and string to an interposed sheet of material by the fastener.
- 25 94. In a machine of the character described the combination of fastener setting 100 means, means to feed a fastener thereto, means to feed a button to position to be affixed by the fastener, means to form a string into a complete loop and means to actuate the fastener setting means to affix 105 the button and string to an interposed sheet of material by the fastener.
- 30 95. In a machine of the character described for affixing a string to a blank, the combination of means to receive a blank in predetermined position, means for setting a fastener through the blank, means for feeding a fastener thereto, means to form washers and feed the same to position to be affixed to opposite sides of the blank by 110 a fastener, means to form a string into a complete loop about the fastener before the fastener is set.
- 35 96. In a machine of the character described for affixing a string to a blank, the combination of means to receive a blank in predetermined position, means for setting a fastener through the blank, means for feeding a fastener thereto, means to supply washers in position to be secured by the fastener against opposite sides of the blank and means to form a string into a complete loop 115 in position to be retained by the fastener.
- 40 97. In a machine of the character described, the combination of means for affix- 120
- 45 125
- 50 130

ing a button to a blank, means for forming a string into a complete loop between the button and the blank and means to actuate the string looping and button affixing means 5 in suitable timed relation to secure the string to the blank by the button.

98. In a machine of the character described, the combination of means for forming buttons on opposite sides of and affixing said buttons to an interposed blank; and means for forming a string into a complete loop between one of said buttons and blank to be secured thereby.

99. In a machine of the character described 15 the combination of means for determining the position of a blank, means for forming and affixing a button and a washer to opposite sides of the blank, means for forming a string into a loop between the button and the blank before the button is affixed and means to actuate the aforesaid means to affix the button washer and string to the blank.

100. In a machine of the character described, the combination with a horn arranged to enter the open end of an envelope, of fastener setting devices operable simultaneously to set fasteners one through the body and one through the flap of the envelope, and means for supplying a length of string in position to be secured by one of the fasteners.

101. In a machine of the character described, the combination with a horn arranged to enter the open end of an envelope of fastener setting devices operable simultaneously to set fasteners one through the body and one through the flap of the envelope, and means for looping a string around one of said fasteners to be secured thereby.

102. In a machine of the character described, the combination with a horn arranged to enter the open end of an envelope of fastener setting devices operable simultaneously to set fasteners one through the body and one through the flap of the envelope, and means for looping a string around one of said fasteners to be secured thereby, and means for supplying a button in position to be affixed by the other of said fasteners.

103. In a machine of the character described for applying fastener devices to an article in predetermined relation to each other, in combination means for positioning a button against and affixing it to one part of the article, means for positioning a button against another part of the article, means for setting a fastener through the last mentioned button and the article and means for actuating the several aforesaid means simultaneously.

104. In a machine of the character described for applying cooperating fastening

means to two parts of an article, in combination, means for affixing metallic fasteners to the article in predetermined spaced relation, and means for supplying in position to be affixed by said fasteners, members arranged to cooperate with each other to constitute a securing device.

105. In a machine of the character described for applying fastener devices to an article, in combination, means for simultaneously applying fasteners to the article in predetermined spaced relation, and means for automatically applying a string in position to be secured by one of the fasteners.

106. In a machine of the character described for applying cooperating fastening means to two parts of an article in combination, means for affixing a pair of fasteners to the article in predetermined spaced relation, means for supplying a flexible member in position to be secured by one of the fasteners of a pair, and means for supplying a button in position to be secured by the other fastener, the flexible member and button being arranged to cooperate to form a securing means.

107. In a machine of the character described, the combination of means for simultaneously affixing a plurality of fasteners to an article in predetermined spaced relation, means for supplying a button in position to be affixed to the article by each fastener, and means to form a string into a loop in position to be secured by one of said fasteners.

108. In a machine of the character described, the combination of means for simultaneously affixing a plurality of fasteners to an article in predetermined spaced relation, means for forming a button in position to be affixed by each fastener, and means to form a string into a loop in position to be secured by one of said fasteners.

109. In a machine of the character described for applying fastener devices to an article, in combination, means for setting eyelets therethrough in predetermined spaced relation and means for supplying a string in position to be secured by one of said eyelets.

110. In a machine of the character described, the combination of two opposed button forming and eyelet setting plungers, dies with which said plungers cooperate to form washers, means for feeding a strip of washer forming material between each die and its cooperating plunger when in retracted position, means for feeding an eyelet into the path of one of the plungers, an annular rotatable string looper concentric with said plungers and through which one of said plungers operates, a parallel washer forming and eyelet setting plunger, a die with which said plunger cooperates to form washers, means for feeding a strip of washer forming material between the die and the

plunger when in retracted position, and means for actuating the plungers simultaneously.

111. In a machine of the character described, the combination with a horn arranged to receive an envelope thereon and having an anvil arranged to enter the open end of the envelope, a washer forming and fastener setting plunger arranged to cooperate with said anvil to set a fastener through the body of the envelope, a die through which said plunger operates, means to feed a strip of washer material along the face of said die, means to feed a fastener into position to be set by said plunger and anvil, a pair of opposed washer forming and eyelet setting plungers arranged to set a fastener through the flap of the envelope, dies through which said plungers operate in approaching fastener setting position, means to feed a strip of washer material along the face of each die, an annular rotatable looper through which one of said plungers operates, means to feed a fastener into position to be set by the plungers, and means to actuate said plungers and looper to substantially simultaneously form washers and affix the same by fastener with a length of string looped beneath one of the washers on the flap.

112. In a machine of the character described, an envelope guide coaxial opposed washer forming and eyelet setting reciprocable plungers, one plunger having a central coaxial eyelet carrying pin, dies on opposite sides of said envelope guide with which said plungers cooperate to form washers, mechanism for feeding strips of washer material along the face of said dies, a rotatable annular looper positioned between said dies and through which one of the plungers operates, means for feeding an eyelet to the eyelet carrying pin, and means for actuating the plungers and looper to form and affix washers to an interposed blank by an eyelet with a string looped around and secured by said eyelet.

113. In a machine of the character described, the combination of opposed eyelet setting plungers, a die with which one of said plungers cooperates to form a washer, means for feeding a strip of material step by step past said die, a washer carrying pin carried by one of the plungers and arranged to enter a previously formed hole in the strip of washer forming material previous to the washer forming cooperation between the plunger and die, a looper arranged to wind a string about said pin, and means to actuate said looper and plungers to affix a washer to an interposed blank by an eyelet with a string looped around and secured by said eyelet.

114. In a machine of the character described, the combination with an envelope receiving and positioning horn of an anvil carried by said horn and arranged to enter the envelope, a reciprocable washer forming and eyelet setting plunger arranged to cooperate with said anvil to set an eyelet through the body of the envelope, a die with which said plunger cooperates to form a washer, means for feeding washer material in front of said die, a pair of opposed washer forming and eyelet setting plungers arranged to set an eyelet through the flap of the envelope, a die adjacent the path of movement of each plunger, means for feeding washer material in front of each die, a rotatable annular looper between said dies and through which one of said plungers operates, arranged to form a string into a complete loop coaxially with said plungers, means to place an eyelet in the path of one of said opposed eyelet sets, means to actuate said opposed plungers, looper and eyelet placing means to affix washers to opposite sides of the envelope flap by an eyelet with a string secured beneath one of the washers.

In testimony whereof, I have signed my name to this specification this 28th day of December, 1917.

HENRY TRENCHARD, JR.
